(57) **CLAIM**

The ornamental design for lateral support arm for attachment to an agricultural stake, as shown and described.

DESCRIPTION

FIG. 1 is a side elevation view of a lateral support arm for attachment to an agricultural stake.

FIG. 2 is a side elevation view, from the side opposite to the view of FIG. 1, of a lateral support arm for attachment to an agricultural stake.

FIG. 3 is an elevation view of the right side end of FIG. 1 or FIG. 2.

FIG. 4 is an elevation view of the left side end of FIG. 1 or FIG. 2.

FIG. 5 is a top plan view of a lateral support arm for attachment to an agricultural stake as shown in FIG. 1 or FIG. 2.

FIG. 6 is a bottom plan view of a lateral support arm for attachment to an agricultural stake as shown in FIG. 1 or FIG. 2.

FIG. 7 is an isometric view of the lateral support arm for attachment to an agricultural stake as shown in FIGS. 1-6; and,

FIG. 8 is an environmental perspective view of the lateral support arms for attachment to an agricultural stake shown in FIGS. 1-7 illustrating in full lines the attachment of two lateral arms to each other and to an agricultural stake (shown in phantom) and illustrating possible additional structures (such as a circular trellis) at the ends of the support arms in operational alignment with possible agricultural elements (shown in phantom).

The broken lines represent environment and portions of the article, and form no part of the claimed design.
